UNITED STATES PATENT OFFICE.

OBADIAH D. HOWARD AND HARRY W. KEEP, OF ST. PAUL, MINNESOTA.

COMB FOR DRYING AND STRAIGHTENING HAIR.

1,349,425.

Specification of Letters Patent. Patented Aug. 10, 1920.

Application filed February 28, 1920. Serial No. 362,166.

To all whom it may concern:

Be it known that we, OBADIAH D. HOWARD and HARRY W. KEEP, citizens of the United States, residing at St. Paul, in the county of Ramsey and State of Minnesota, have invented certain new and useful Improvements in Combs for Drying and Straightening Hair, of which the following is a specification.

10 This invention relates to combs and more particularly to the type of comb adapted to be heated for the purpose of drying the hair.

15 A further object of the invention is to provide a comb wherein the teeth are formed with flat surfaces adapted to contactingly mesh with the surfaces of the oppositely disposed teeth, the teeth being movable with reference to each other at the will of the operator.

20 A still further object of the invention is to provide a comb which may be heated both electrically or otherwise, the comb being constructed so as to fit standard makes of electric heating units, but which may also be mounted on a solid staff.

The invention consists in the construction, combination and arrangement of parts hereinafter described and claimed.

In the drawings:

30 Figure 1 is a side elevation of the invention showing it applied to an electric heated handle of standard make.

35 Figs. 2 and 3 are enlarged end views of the invention shown respectively in open and closed position.

Fig. 4 is a sectional view on line 4—4 of Fig. 2.

Fig. 5 is a sectional view on line 5—5 of Fig. 2.

40 Fig. 6 is a sectional view on line 6—6 of Fig. 3.

Fig. 7 is a sectional view on line 7—7 of Fig. 3.

45 Fig. 8 is an enlarged view of a number of teeth of the comb, disclosing the contour and intermeshing feature thereof.

Figs. 9 and 10 are fragmentary perspective views respectively of the two halves of the comb.

50 Fig. 11 is a fragmentary perspective view of the finger lugs for operating the comb members, and

Fig. 12 is a plan view of the same.

In the drawings, A represents a handle secured on the stem B, the latter being tubu-

lar in form and containing an electric heating element (not shown) connected with the conductors C, which latter are connected with a source of electric current. The heating element is of standard make of which there are several, it not being thought necessary to illustrate the interior thereof, the stem B of the form shown being cylindrical and of uniform diameter but the end adjacent the handle A being for a distance 65 hexagonal in cross section as at D. Thus applicants' comb may be applied to any other type of heating device, the hexagonal section in the type shown serving as a means for preventing the comb from rotating 70 thereon.

Applicants' comb consists of the toothed members E, and F respectively hinged together so as to open like a book each wing thereof being formed with comb teeth 1, the 75 teeth of the members being disposed in offset relation so that the teeth of one member will enter the space between the teeth of the opposite member. Each of the toothed members consists of a comparatively long narrow 80 plate-like portion 2 having along its upper edge hinge members 3 and 4 respectively. The toothed member E has at one end a hexagonal socket 5 in alignment longitudinally with its hinge member and adapted to frictionally fit over the portion D of the heating element. The hinge member 3 fits between the hinge member 4 and the socket 5 so that the stem B of the heating device may be inserted longitudinally of the toothed member 90 so as to hinge them together as shown in Fig. 1. The member F will be movable relative to the member E so as to swing around the longitudinal axis of the stem B. In order to limit the swing thereof a pin 95 6 is provided, said pin being disposed radially on the hinge member 4 so as to engage the edge 7 of the toothed member. Thus, as indicated in Fig. 2 the two comb members are held restricted in their swinging movement relative to each other so that the opening at 8 will be sufficient to permit a suitable quantity of hair to enter the space between the teeth in the process of combing.

In Fig. 3 the two comb members are shown 101 in the process of gripping a wisp of hair, the two members having been brought together for that purpose.

Referring to Fig. 7 of the drawings, the teeth 1 are shown regularly spaced, a part 111

of each tooth being as shown in Figs. 4 and 6 triangular in cross section, the apex 9 of the teeth of the comb member being adjacent each other. The bases 10 of the 5 triangular sections coincide with the outer face G of the comb members, the latter being convex in form so as to facilitate combing of the hair.

As shown in Fig. 5, the teeth are chamfered to form oppositely disposed angular faces 11 on either side of the teeth adjacent the back thereof, this chamfer forming the oblate cavity 12 on the outside of the comb whereby is formed a wide funnel-like 10 mouth for the hair to enter as it is drawn therethrough.

In Figs. 6 and 7 the teeth of the comb members are shown in ironing position; that is, the flat faces 13 of the teeth are 15 engaging the strand of hair from opposite sides so as to iron out any kinks that may be therein. When the teeth are in the position shown in Figs. 6 and 7, the faces 13 are disposed parallel to each other. Integrally respectively with the members E and F and projecting rearwardly therefrom and located adjacent to the handle, are the finger lugs 14 disposed opposite one another and being provided with an insulator finger piece 15 so as to insulate the hand from the heat. Between the two finger lugs 14 is an outwardly pressing spring 16, said spring being anchored at its respective rearward ends in the respective openings 17 of 20 the lugs. Thus, by means of the spring the two comb members are held constantly in the position shown in Fig. 2. In the process of combing, however, when the comb is projected into the hair, the operator 25 presses inwardly on the thumb pieces 15 of the member F, whereby the two members are brought together to engage the hair frictionally. Obviously, any desired pressure 30 may thus be exerted on the hair the degree depending on the operator.

We claim:

1. A comb consisting of two members hinged longitudinally together at one edge, a row of teeth on the opposite edge of each member the teeth of one member being disposed opposite the spaces between the teeth of the other member and being projectable into said spaces, and means for yieldingly holding said members in spaced relation for the purpose set forth.

2. A comb consisting of two elongated members pivotally joined together to open like a book, a row of teeth for each of said members disposed approximately radial with the pivot of said pivot joint and extending outwardly therefrom and disposed at right angles thereto, the row of teeth of one member normally loosely meshing with the row of teeth of the other member, and means for yieldingly holding said rows of teeth in their normal relative position.

3. In a comb the combination with a cylindrical rod-like heating unit, two comb members normally arranged flatwise one immediately adjacent the other the teeth of 70 said members being adapted to contactingly mesh with one another sidewise throughout their length and pivotal supporting means on each of said members to frictionally surround said rod-like unit so as to be swingable thereon toward and away from each other.

4. In a comb the combination with a rod-like heating unit, two comb members pivotally mounted on said rod-like unit so as to 8 swing like the covers of a book the teeth of said members intermeshing when the latter are folded against each other, and means for yieldingly holding said members slightly separated.

In testimony whereof we affix our signatures.

OBADIAH D. HOWARD.
HARRY W. KEEP.
